UNITED STATES PATENT OFFICE.

CATHERINE O'HARA, OF NEW YORK, N. Y., ASSIGNOR TO THE BUTTERICK PUBLISHING CO., (LIMITED,) OF SAME PLACE.

DESIGN FOR A LADY'S WALKING-SKIRT.

SPECIFICATION forming part of Design No. 14,381, dated October 30, 1883.

Application filed August 23, 1883. Term of patent 3½ years.

To all whom it may concern:

Be it known that I, CATHERINE O'HARA, of the city, county, and State of New York, have invented and produced a new and Original Design for a Pattern of a Lady's Walking-Skirt, (numbered 8,826;) and I do hereby declare that the engraved prints accompanying this specification convey to any one accustomed to using paper patterns a clear understanding of how a garment made up by the pattern will appear.

The design combines a walking-skirt with a short apron drapery, a scarf drapery, a full

pointed back drapery, and a panel drapery, the apron, scarf, and back draperies being all draped by plaits.

What I claim as my invention, and desire to secure by Letters Patent, is—

The design for a lady's walking-skirt, as shown in the engraved prints accompanying this specification.

CATHERINE O'HARA.
